UNITED STATES PATENT OFFICE

CHARLES J. KNIPP, OF NEAR TIPTON, MISSOURI

HARROW

Application filed March 28, 1930. Serial No. 439,804.

This invention relates to new and useful improvements in agricultural implements or machines and more particularly to devices of this character of the type known as disc 5 harrows.

The primary object of the invention is to provide, in a manner as hereinafter described, a disc harrow embodying a novel construction and arrangement of parts whereby the angularity of the discs may be expeditiously 10 adapted and secured in adjusted position while the harrow is in operation and without the necessity of stopping the same.

Other objects of the invention are to provide a harrow of the aforementioned character which will be simple in construction, strong, durable, efficient in its use and which may be manufactured at low cost.

All of the foregoing and still further objects and advantages of the invention may 20 become apparent from a study of the following specification, taken in connection with the accompanying drawings wherein like characters of reference designate corresponding parts throughout the several views, and wherein:

Figure 1 is a top plan view of a disc harrow constructed in accordance with this invention.

Figure 2 is a view in side elevation thereof.

Figure 3 is a fragmentary view in bottom plan showing the means of adjustably securing the plate to the beam.

Figure 4 is a cross sectional view taken substantially on the line 4-4 of Figure 2 looking in the direction of the arrows.

Figure 5 is a fragmentary view in rear end elevation showing the means for pivotally connecting the discs to the plate.

Referring to the drawings in detail, it will be seen that the reference numeral 1 designates an elongated longitudinally extending beam of substantially inverted U-shaped cross 45 section and having a longitudinal slot in its forward end portion and a pair of spaced longitudinal slots 3 in its rear end portion. Mounted for longitudinal sliding adjustment on the rear end portion of the beam 1 is a horizontally disposed plate or platform 4

which is slidably secured on said beam through the medium of the bolts 5 which extend slidably through the slots 3. As clearly illustrated in Figure 1 of the drawings, the opposite sides of the plate or platform 4 are 55 curved and converge forwardly and an integral upstanding marginal flange 6 is provided on said plate.

A lever 7 is pivotally mounted on the beam 1 at an intermediate portion thereof as designated at 8 and a segment 9 is also rigidly secured on the beam 1 for receiving a spring 60 pressed detent 10 operatively mounted on the lever 7 for securing said lever in adjusted position. A bar 11 is pivotally secured to the lever 7 as at 12 and extends rearward therefrom and has its forward end secured to the rear portion of the plate 4. A bar 13 also is pivotally connected to the lever 7 at 12 65 and extends forwardly therefrom in a substantially horizontal plane and has its forward end pivotally and adjustably connected to the upper end portion of an arm 14 which extends for swinging movement through the slot 2 in the beam 1 and is pivotally supported between the free ends of the hangers 15 which are secured to the opposite sides of the beam 1. This construction is best illustrated in Figure 4 of the drawings. As clearly seen in Figure 2, the bar 13 and the arm 14 are each 70 provided with a series of spaced holes which are adapted to be selectively brought into registry with each other to adjustably couple said bar and arm together. A coupling element 16 is pivotally mounted on the arm 14 75 beneath the beam 1 to connect the harrow to a suitable draft implement such as a tractor.

A pair of bars 17, preferably of angle iron, are pivotally mounted, as at 18, beneath the plate 4 and adjacent opposite sides of the 80 rear end portion of the beam 1. As best seen in Figure 1 of the drawings, the bars 17 extend substantially parallel with the rear edge of the plate 4 and project beyond the opposite side of said plate. The bars 17 are 85 adapted for swinging movement in a horizontal plane beneath the plate 4 and have secured to their upper sides adjacent their outer ends a pair of brackets 19 which slidably engage over the flange 6 on said plate 4. Said 90

100

brackets constituting means for supporting the outer end portions of the bars in a manner to permit swinging movement thereof. Arms 20 depend from the opposite end portions of the bars 17 and are provided in their free end portions with bearings for rotatably supporting the shafts 21 upon which are mounted the harrow discs 22. Rearwardly diverging brace arms 23 are secured to opposite sides of the beam 1 and have their rear ends loosely connected to the forwardly projecting angular end portions 24 of the outermost of the shaft supporting arms 20, as clearly illustrated in Figures 1 and 2 of the drawings. Additional braces 24 are connected to the outer portions of the brace arms 23 and extend upwardly therefrom and have their upper ends anchored to the bars 17. Braces 25 are pivotally connected for swinging movement at 26 to the plate 1 and extend downwardly and rearwardly therefrom and are connected to the forwardly projecting portions 27 of the innermost of the arms 20.

In use, the operator swings the lever 7 on its pivotal mounting 8 and the plate 4 is thus moved longitudinally on the beam 1 through the medium of the connecting bar 11. Sliding movement of the plate 4 imparts swinging movement to the bars 17 through the medium of the pivotal connection 18 between the plate and the inner end portion of each of said bars. As before stated, the connection between the brace arms 23 and the portions 24 of the outermost of the arms 20 and also between the additional braces 24 and the bars 17 will permit swinging movement of said bars 17 thereon. The connection between the inner braces 25 and the portions 27 of the innermost arms 20 is also sufficiently loose to permit the slight swinging movement of the bars 17 which would occur at this point.

It will thus be seen that I have provided a harrow wherein the angularity of the discs with respect to the direction of travel of the harrow may be expeditiously adjusted while the device is in operation.

It is believed that the many advantages of a disc harrow constructed in accordance with this invention will be readily understood, and although the preferred embodiment of the invention is as illustrated and described, it is to be understood that changes in the details of construction may be had which will fall within the scope of the invention as claimed.

What is claimed is:—

1. A harrow of the character described comprising a beam, a plate slidably mounted for longitudinal movement on the beam, a pair of bars pivotally connected, at their inner ends, to the plate on opposite sides of the beam, braces secured to the beam and loosely connected to the bars, a shaft secured to each bar in spaced relation thereto, harrow discs

mounted in spaced relation on each of the shafts and means mounted on the beam for shifting the plate longitudinally in a manner to swing the bars in a horizontal plane.

2. A harrow of the character described comprising a beam, a plate mounted for longitudinal sliding movement on the beam, an upturned flange formed integrally on the marginal portion of the plate, a pair of bars pivotally mounted at their inner ends to the plate on opposite sides of the beam, braces secured to the beam and loosely connected to the bars, brackets extending upwardly from the bars and slidably engaged over the flanges in a manner to support the outer end portions of said bars for swinging movement in a horizontal plane beneath the plate, a shaft mounted beneath each bar in spaced relation thereto, harrow discs mounted on each shaft and manually operable means mounted on the beam for shifting the plate longitudinally on said beam.

3. A harrow of the character described comprising a beam, a plate mounted for longitudinal sliding movement on the rear end portion of the beam, an integral upturned flange on the marginal portion of the plate, a pair of bars pivotally connected at their inner ends beneath the plate for swinging movement in a horizontal plane thereon, brackets secured to the outer portions of the bars slidably engaged over the flanges on the opposite side of the plate in a manner to support the outer portions of the bars for swinging movement therebeneath, means for shifting the plate horizontally and longitudinally on the beam in a manner to swing the bars, braces extending outwardly from the beam and pivotally connected to intermediate portions of the bars to permit the same to be swung by the plate and harrow gangs mounted on said bars.

In testimony whereof I affix my signature.

CHARLES J. KNIPP.
